DESIGN FOR A DRESS

Frederick Wilkins, Brooklyn, N. Y.

Application January 11, 1941, Serial No. 97,998

Term of patent 3½ years

To all whom it may concern:

Be it known that I, Frederick Wilkins, a citizen of the United States, residing in New York city, in the county of Kings and State of New York, have invented a new, original, and ornamental Design for Dresses, of which the following is a specification, reference being had to the accompanying drawing, forming part thereof, in which—

Figure 1 is a front view of a dress, showing my new design; and

Figure 2 is a rear view thereof.

The characteristic feature of my design resides in the combination on the specific dress disclosed of a set-in rectangular piece of fabric integral with the skirt, adjacent to and below the front waist of said skirt, having a lace edging around said rectangular piece and matching lace edging on the sleeve cuffs of said dress, as shown.

I claim:

The ornamental design for a dress, as shown and described.

FREDERICK WILKINS.
